UNITED STATES PATENT OFFICE

2,191,505

MANUFACTURE OF WINDOW ENVELOPES

Ferdinand L. Smithe, New York, and Abraham Novick, Flushing, N. Y., assignors to F. L. Smithe Machine Co., Inc., New York, N. Y., a corporation of New York

Application July 13, 1934, Serial No. 734,978
Renewed October 6, 1938

14 Claims. (Cl. 271—1)

This invention relates to the manufacture of window envelopes and is in the nature of an improvement upon the invention disclosed in Letters Patent of the United States #1,827,539, granted to Abraham Novick on October 13, 1931.

In common with the procedure followed in the invention of said patent, provision is made for operating on envelopes having window openings cut in the bodies thereof. The securing flaps of the blanks are first gummed, and the blanks in fanned-out condition are carried by a drying conveyor to the subsequent operating instrumentalities. Such instrumentalities comprise means for realigning the blanks in spaced out condition as they are delivered by the drying conveyor, means for applying gum to the window margins and securing window patches to the blanks, and means for thereafter adhesively uniting the side and bottom flaps of the blanks.

It is an important object of the present invention to provide for the transferring and spacing out of the blanks as they leave the drying conveyor in such manner that all liability of a window edge of one blank catching a window edge of an adjacent blank is avoided. To this end it is a feature that the blanks delivered by the drying conveyor in one path are projected across a gap so that they may bend down under the influence of gravity and that the next subsequent blank feeding means is located in a lower plane than the path of delivery of the blanks. Provision is made in the plane of said second feeding mechanism of means for intercepting the leading edges of the blanks and limiting bending of the blanks. The arrangement is such that the window area of each blank bridges across the gap out of contact with the window areas of adjacent blanks, so that when rapid advance of the leading blank takes place, the blank is free to advance without obstruction.

Other objects and advantages will hereinafter appear.

In the drawings forming part of this specification:

Fig. 1 is a fragmentary view in side elevation, largely diagrammatic, illustrating a portion of the drying conveyor and of the feeding and aligning mechanism to which the blanks are delivered by the drying conveyor;

Fig. 2 is a view in sectional elevation illustrating an end portion of the drying conveyor and a series of instrumentalities for acting on the blank after it has left the drying conveyor;

Fig. 3 is a plan view of a bed cylinder which

supports the blank during application of a patch thereto;

Fig. 4 is a fragmentary plan view of the mechanism of Fig. 2;

Fig. 5 is a fragmentary diagrammatic view in side elevation on a larger scale than the preceding figures, illustrating the transfer of the blanks from the drying conveyor to the blank spacing and feeding mechanism;

Fig. 6 is a fragmentary detail view partly broken away illustrating the patch feeding, cutting and applying mechanism;

Fig. 7 is a sectional view illustrating the patch transferring and applying segment at a different point in the cycle from that illustrated in Fig. 6;

Fig. 8 is a view in sectional elevation illustrating mechanism for variably driving the patch transferring and applying segment;

Fig. 9 is a view in sectional side elevation, partly broken away and largely diagrammatic, illustrating a modified form of machine, and

Fig. 10 is a plan view of an envelope blank as supplied to the machine of Fig. 9.

The envelope blanks 1 each comprising a sealing flap 2, a bottom flap 3, side flaps 4 and a body portion having a window opening 5 provided therein, are supplied to the machine and gummed along the margins of the sealing flaps in any suitable manner, for example, in the manner illustrated in my patent referred to above. The blanks are then delivered in overlapped or fanned-out relation to a drying conveyor 6, to which they are clipped. The drying conveyor runs around a cylinder 7 and carries the blanks onto an extensible table 8 comprising relatively adjustable sections 9 and 10. The conveyor 6 comprises chains 11 which run at the delivery end of the conveyor upon sprockets 12 which are fast upon a shaft 13. The shaft 13 also has fast upon it a feed roller 14 which cooperates with a lower feed roller 15 for delivering the blanks away from the conveyor. Provision is made for adjusting the shaft 13 and the roller 15 longitudinally of the table 8, and for appropriately readjusting the chains 11. The table 8 desirably extends substantially horizontally and is adjusted to terminate in line with the line of contact of the rollers 14 and 15. The blanks are delivered with the gummed margins of the sealing flaps faced upward and trailing.

The overlapped blanks issue from between the feed rolls 14 and 15 in the manner indicated in Fig. 5. In this figure the marginal portions of the blanks which border upon the window openings are shown cross-hatched for the purpose of

indicating the window areas of the blank. The blanks are unsupported for a space after they leave the feed rolls 14 and 15 and they therefore bend downward under the force of gravity until their leading edges are intercepted and supported by a table 16 which is located in a lower plane than the table 8 and which desirably extends substantially parallel to the table 8. The upper surface of the table 16 stands substantially tangent to a pair of feed rollers 17 which are fast upon a shaft 18. The shaft 18 also has fast upon it a pair of sprockets 19 upon which parallel chains 20 run at the same linear speed as the peripheral speed of the rollers 17. The upper stretches of the chains 20 travel in the plane of the top of the table 16 and the chains are provided with transversely aligned pins 21 which travel in unison and which are adapted to engage in the angles of the blank formed at the junctions of the sealing flap with the side flaps. Sectors 22, fast upon a shaft 23, are driven in unison with the rollers 17 and the conveyor chains 20.

As seen in Fig. 5 the leading blank 1^a is in a position in which it is gripped between the rollers 17 and the sectors 22 to be fed rapidly forward. In this action it should be observed that the sectors 22 and the rollers 17 engage the blank outside the lateral bounds of the window area so that they do not act upon the forward extremity of the blank at the middle of the bottom flap. The blank 1^a is also nearly ready to leave the bight of the rollers 14 and 15. The forward end of the blank bridges the space between the roller 15 and the table 16 and stands out of contact with the blank 1^b. When the sector reaches blank-engaging position the blank 1^a is in position to be gripped and advanced rapidly by the sector and the sector then advances the blank rapidly to locate the trailing edge of the blank in position to be engaged and pushed forward by a pair of pins 21. The sectors again become ineffective, however, before the leading edge portions of the blank 1^b which can be engaged by the sectors 22 have been advanced far enough to be engaged by the sectors. It will be observed that during the movement of the blank 1^a relative to the blank 1^b, because of the bridging action, the blank 1^a is entirely out of contact with the blank 1^b in the overlapping window areas of the blanks, so that there is no danger of the trailing edge of the window of blank 1^a catching upon the leading edge of the window area of blank 1^b. It is to be noted that the bite of the roll 14 is suitably regulated to effect the necessary feeding action without exerting such a drag upon the trailing end thereof as to cause rupture of the blank when the sectors 22 enter into engagement with the leading edges at the side of the blank (see Fig. 4).

Sometimes a tongue 23^a may be used to assist in bending the blank 1^b away from the blank 1^a, said tongue extending down through the window opening 5 of the blank 1^a to the blank beneath. The tongue 23^a is especially advantageous when the blanks are composed of heavier weight material or when the material has a reverse curl. The tongue 23^a is sufficiently resilient to lift out of the window opening while the upper blank is being fed from the position in Fig. 5.

After the rollers 17 and the sectors 22 have acted to pull the leading blank substantially clear of the pack the blank is overtaken by the pair of pins 21 and advanced in definitely timed and aligned condition to subsequent operating instru-

mentaries. The chains 20 travel at their discharge ends upon sprockets 24 and the table 16 terminates a little beyond these sprockets. A feed roller 25 and cooperating feed segments 26 which travel a little faster than the chains 20 act to pull the blanks away from the pins 21 and to feed them between opposed lower and upper conveyors 27 and 28. The conveyor 27 comprises a pair of laterally spaced belts 29 and the conveyor 28 comprises a pair of similarly spaced, opposed belts 30. The belts 29 run upon end rollers 31 and 32, upon a roller table between the end rollers consisting of a series of rollers 33, supported on stub shafts 33^b, and upon idler rollers 34 and 35. The belts 30 run upon end rollers 36 and 37 and upon idler rollers 38 and 39. The rollers 33 of the roller table are supported on suitable plates, not shown, at their outer ends, and they are arranged with their axes disposed upon an arc of slight curvature so that the upper stretches of the belts 29 are slightly convex. This convexity of the lower belt contributes substantially to the secure gripping of the blanks between the belts since it causes the belts 30 to exert positive pressure against the belts 29 at all points between the end rollers 36 and 37.

The conveyors 27 and 28 carry the blanks in definitely timed relation past a gumming segment 40 which travels at a peripheral speed equal to the linear speed of the conveyors 27 and 28. Gum is applied to the segment 40 from a gum pot 41 by means of a gum take-up roller 42 which runs in the pot 41 and a gum transfer roller 43 which stands in contact with the roller 42 and tangent to the path of the gumming segment 40. The gumming segment 40 operates between the belts 30 to apply gum to the margins of the blank which border upon the window opening. Opposite the gumming segment 40 provision is made of a bed cylinder 44 which runs in a water receptacle 45. When a gap occurs in the normal sequence of blank delivery gum applied to the bed cylinder 44 is carried into the water in the receptacle 45. A submerged scraper or brush 46 assists in wiping the gum from the face of the bed cylinder 44 and a further scraper 47 wipes the water from the bed cylinder as the cylinder emerges from the receptacle.

The gummed blank is also advanced by the conveyors 27 and 28 past a patch applying mechanism. This mechanism comprises a supply reel 49 from which a web 50 of transparent patch material is drawn by continuously operating feed rollers 51 and 52. The patch material is fed onto a table 53, the forward edge of which is provided with a shearing block 54 forming one element of a patch severing device. A blade 55 is adapted to co-act with the block 54 being carried by a rocking frame 56 which is normally held up by a spring 57 connected to an ear 58 of the rocking frame and to a fixed frame member (not shown). The rocking frame is provided with a roller 59 which serves as a cam follower for engaging the periphery of a rotating cam 60. The cam 60 is of generally circular contour but is provided with a hump 61 which acts upon the follower 59 to depress the rocking frame at the appropriate time in the cycle of operations to cause a patch to be severed. The roller 52 is journaled in a further rocking frame 62 carried by a rock shaft 63. One member of the frame 62 is provided with a tail portion 64 which engages a disc 65. The disc 65 is rotatably mounted upon a shaft 66. The disc 65 has a flat 67 against which the tail 64 normally rests and this permits the roller 52 to

normally to co-act with the roller 51. The disc 65 may be turned by means of a handle 65^a to raise the tail 64 to lift the roller 52 out of engagement with the roller 51 to facilitate the insertion of a fresh patch web. A spring 68 connected to an arm 69 of the frame 62 and to a fixed part of the machine frame acts to urge the frame 62 counter-clockwise and hence to urge the roller 52 toward the roller 51.

10 The leading end of the web 50 which protrudes beyond the cutting block 54 extends into the path of a patch transferring and applying segment 70 which travels about a hollow shaft 71 and cooperates with a bed cylinder 70^b. The segment 70 travels into supporting relation to the web end lifting it to the position illustrated in Fig. 7, where the patch web 50 is sucked against it while it is slack. The segment 70 then travels further dragging over the surface of the web to the position in Fig. 6 where the web is taut. In the position of Fig. 6 the cutting device is about to operate. At the instant of patch severance the leading edge of the web stands between the leading edge of the cylindrical surface of the segment 70 and a row of suction passages 72 provided in the segment near the leading edge thereof. The segment 70 carries the severed patch around and co-acts with the bed cylinder 70^b to press the patch in proper position against the gummed envelope blank.

30 The segment 70 is carried by a rocker arm 74 which is mounted upon a shaft 75 journaled in a crank 76 fast on the shaft 71. A tail portion 77 of the rocker arm 74 is drawn toward the axis 35 of the shaft 71 by a spring 78 connected to such tail portion and to a pin 79 which travels with the shaft. The tendency of the spring 78 is to project the segment 70 outward away from the axis of the shaft 71. The outward limit of movement of the segment is controlled by an adjusting screw 80 which is threaded through the tail portion 77 and which engages a hub 81 of the crank 76. A lock nut 82 is provided for maintaining the screw 80 in adjusted position. With 40 this arrangement the segment 70 is adapted to yield when it engages the envelope blank and hence to apply the patch with light but firm and substantially uniform pressure to the blank. The arrangement disclosed does not ordinarily require 45 resetting for operating upon blanks of different thickness nor is it affected by any moderate amount of wear.

50 The suction is applied to the passages 72 through passages 83 and 84 formed in the segment 70 and the rocker arm 74. The passage 84 communicates through a nipple 85 with a flexible tube 86. The tube 86 in turn communicates through a nipple 87 with a radial passage 88 of the shaft 71. The passage 88 communicates 55 through the axial passage 89 of the shaft 71 with a suitable source of suction. The flexible tube 86 turns with the shaft 71 and is adapted to yield to accommodate such movements of the segment 70 relative to the shaft 71 as occur in the normal 60 operation of the machine and also such movements as may be produced by adjustment of the screw 80.

65 After the patch is applied to a blank the blank is delivered by the conveyors 27 and 28 to a subsequent conveyor 90 whereby it is delivered to the other instrumentalities for completing the manufacture of the blank into a finished envelope.

70 In Fig. 8 disclosure is made of mechanism for driving at variable speed the shaft 71 whereby the segment 70 is carried. The driving means is so

constructed and arranged that the segment is caused to come to rest substantially simultaneously with the severing of a patch, and to be thereafter smoothly accelerated to the speed of the envelope blanks so that the segment travels 5 in unison with a blank when applying a patch to it.

75 A gear 91 is secured to a shaft 91^b, and rotates at uniform speed, to drive a gear 92, which is journaled on the shaft 71, at uniform speed. The gear 92 has fast upon it a block 93 to which a link 94 is pivotally connected. The link 94 forms one member of a toggle or knuckle, the other member of the toggle or knuckle being a link 95. Both of the links 94, 95 are pivotally connected to 15 a pin 96 which carries a cam following roller 97. The end of the link 95, remote from the pin 96 is pivotally connected, by means of a pin 98^a, to a crank 98 which extends outward from a collar 99, the collar being made fast to the shaft 71 by 20 means of a pin 100. The roller 97 runs in a cam track 101 provided in a cam 102. The cam 102 is mounted upon a stationary plate 103, being adjustable relative to the plate about the axis of the shaft 71. Marginal portions of the plate 103 25 are provided with arcuate slots 104 concentric with the shaft 71, and the cam is clamped in place by means of bolts 105 and clamping nuts 106.

30 If the cam block 101 were circular and concentric with the shaft 71, the gear 92 and the shaft 71 would obviously rotate in unison at all times. The cam, however, is so designed that the uniform rotation of the gear causes the shaft 71 to come to rest for a brief period just as the patch 35 is severed and then to be accelerated to the speed of the envelope blanks. This result is very readily and simply achieved by making a portion of the cam track, bounded by the lines 95^a and 95^b, concentric with a point in the circular path of the 40 axis of the pin 98^a. When the roller reaches the portion of the cam track referred to, it is incapable of moving otherwise than about the center of the pin 98^a, and hence during this interval the link 95 has only pivotal movement and no 45 bodily or translational movement. The center of the pin 98^a is therefore held stationary with the result that the crank 98, the shaft 71, and the segment 70 are held stationary.

50 In the ultimate result, the patch segment is driven substantially the same as the patch transfer disclosed and claimed in Letters Patent of the United States, No. 1,831,575 granted to Abraham Novick on November 10, 1931. Structurally, however, the mechanism of the present application is simpler. The patch segment of the present application, moreover, applies the patch directly to an envelope blank, there being no intermediate transfer of the patch to a separate applying member.

55 The cam is made adjustable in order to cause the period of rest to occur at the point in the revolution of the segment 70 appropriate to the length of patch employed. When long patches are used, the segment should come to rest a little 60 later in the cycle than when short patches are used, so that the leading edge of the patch will always be located a little in advance of the suction passages 72 at the moment of severance. Different lengths of patches are provided by 65 changing gearing in the driving train of the patch web feeding roller 51.

70 It is, of course, intended that an envelope blank will always be present and ready to receive a patch at the time that the patch applying seg- 75

ment comes opposite the bed cylinder 70^b. It occasionally happens, however, that a gap occurs in the series of blanks. Under such circumstances, it is not desirable to permit the unused patch to get into the machinery. Provision is accordingly made in the bed cylinder 70^b of a series of suction passages 107 for securing the patch to the bed cylinder when no blank is present. These suction passages are so located in the bed cylinder that they normally engage a margin of the envelope blank bordering upon the window opening so that the suction is not applied to the patch at all when the blank is present. The suction passages, therefore, have no tendency to disarrange the patch with reference to the blank in normal operation. When the suction passages do take control of the patch, however, in the absence of a blank, the bed cylinder 70^b carries the patch around with it until it is intercepted and caused to be stripped off by suitable fingers 108 which lie in circumferential grooves 109 formed in the periphery of the bed cylinder 70^b. The unused patch is thus disposed of in an orderly manner.

At times there is a tendency for the envelope blank to adhere to the cylinder 70^b and follow it around. To avoid this there is provided a stripper 110 which is normally away from the cylinder and is supported by an arm 110^a on a shaft 30 110^b. Just before the leading edge reaches the stripper the latter is moved against the cylinder to deflect the blank therefrom and the stripper then returns to its normal position (Fig. 2). This occurs before the window patch reaches 35 the stripper so that the patch may pass around the cylinder to be thrown out in the absence of an envelope blank.

In Fig. 9 disclosure is made of a modified form 40 of window envelope machine which is adapted to deal with whole blanks which are either supplied to the machine with the sealing flaps already gummed, or which are intended to be manufactured into second class envelopes. Many of 45 the elements of this machine are duplicates of elements Figs. 1-8. As to such elements the same reference numerals have been applied with the superscript "a" added and these elements will not be described in detail.

In the machine of Fig. 9, whole blanks 110^a are supplied from a stack 111 which is supported 50 by a magazine 112. The blanks are taken from the stack by a mechanism like that disclosed in Figs. 10-16 inclusive of the pending application of Abraham Novick, Serial No. 628,302, filed August 11, 1932, for Envelope machines. Such mechanism comprises a supporting or detaining plate 113, a suction picker 114, a separator 115, a cylinder 116, and oscillatory auxiliary rollers 118. The suction picker moves into engagement with the exposed margin of the bottom-most blank 60 and then away from the stack to draw the edge of the bottom-most blank past the supporting or detaining finger 113. While the picker 114 holds a margin of the lower-most blank thus separated from the stack, a pair of dagger members is moved forward into the space between the stack and the partially separated blank to move the edge of the partially separated blank into proximity to the cylinder 116. After the separator members have entered the spaces between the stack and the margin of the bottom blank, the suction picker 114 is withdrawn longitudinally of the plane of the blank to permit the blank to clear it. The dagger members of the separator 70 75 115 press the margin of the blank close to but

not into gripped relation with cylinder 116. The auxiliary rollers 118, which run constantly in engagement with the cylinder 116, are moved counter-clockwise about the axis of the roller 116 into position to grip the leading margin of the 5 blank. The blank is advanced by the cylinder 116 in cooperation with roller 119 onto a table 120, being taken up, aligned and advanced by a conveyor 20^a and delivered to conveyors 27^a and 28^a. As the blank is advanced by the latter conveyor, it is fed first past a window cutting die 121 which coacts with a bed cylinder 122. The bed cylinder is provided with pins 123 which penetrate the window chip and carry it around to be discharged by a stripper member 124. From this point the parts disclosed are all duplicates of the parts disclosed in Figs. 1 to 8, and no further detailed description is therefore deemed necessary.

The mechanism disclosed herein, and in the pending application of Abraham Novick, Serial No. 738,095 (now Patent No. 2,125,308) for feeding a patch to a blank and applying the patch to the blank is not claimed herein, but is claimed in our divisional application, Serial No. 18,402, filed April 26, 1935, for Manufacture of window envelopes.

We have described what we believe to be the best embodiments of our invention. We do not wish, however, to be confined to the embodiments shown, but what we desire to cover by Letters Patent is set forth in the appended claims.

We claim:

1. In a machine for making window envelopes, in combination, means for delivering window blanks in a fanned out pack with the overlapping bodies of the leading blanks free from contact with each other in the window areas, and means for engaging the leading margin of the foremost blank in advance of the leading margin of the second blank and pulling the foremost blank clear of the pack.

2. In a machine for making window envelopes, in combination, means for delivering fanned out window blanks divergently so that the window areas of adjacent blanks are out of contact, and means for advancing the foremost blanks clear of the others.

3. In a machine for making window envelopes, in combination, means for delivering fanned out window blanks with the leading portions thereof unsupported, means standing in intersecting relation to the direction of delivery of the blanks to deflect the blanks successively and progressively, to space the window areas of the leading blanks from one another, and means for advancing the leading blank relative to the others.

4. In a machine for making window envelopes, in combination, means for delivering fanned out window blanks with the leading ends thereof unsupported so that they droop under the influence of gravity, means for intercepting and deflecting the leading edges of the blanks successively to separate the window area of the leading blank from the window area of the next blank, and means for advancing the leading blank relative to the others.

5. In a machine for making window envelopes, in combination, means for delivering window blanks with each blank protruding at the leading margin thereof beyond the leading edge of the next underlying blank, and means extending in intersecting relation to the direction of movement of the delivered blanks to deflect and lift

the windowed portion of each blank away from the following blank.

6. In a machine for making window envelopes, in combination, means for feeding window blanks in fanned out relation, said feeding means terminating abruptly and discharging the blanks with the leading ends unsupported, and a table extending across the direction of delivery of the blanks to receive the leading edges of the blanks serially as each such edge becomes unsupported, and to cause each blank as its edge engages and moves along the table to bridge the space between the feeding means and the point of contact with said table, in such fashion that the windowed portion of each blank is self-sustained out of contact with the underlying body of the following blank.

7. In a window envelope machine, in combination, means for delivering window blanks with each blank protruding at the leading margin thereof beyond the leading edge of the next underlying blank, means extending in intersecting relation to the direction of movement of the delivered blanks to deflect and lift the windowed portion of each blank away from the following blank, and supplemental deflecting means to depress each blank away from the overlying preceding blank.

8. In a window envelope machine, in combination, means for delivering window blanks with each blank protruding at the leading margin thereof beyond the leading edge of the next underlying blank, and means extending in intersecting relation to the direction of movement of the delivered blanks to deflect and depress each blank away from the windowed portion of the preceding blank.

9. In a window envelope machine, in combination, means for delivering window blanks with each blank protruding at the leading margin thereof beyond the leading edge of the next underlying blank, and means extending in intersecting relation to the direction of movement of the delivered blanks to deflect each blank away from the windowed portion of the adjacent blank.

10. A mechanism for advancing windowed envelope blanks serially from contiguous fanned-out positions, said mechanism comprising the elements combined and cooperating as set forth in claim 9, and further characterized by having said deflecting means formed as a finger disposed in position to traverse the window opening of an overlying blank into depressive engagement with the body of the next underlying blank, and eventually to be raised from such traversing position by advance of a margin of said window.

11. In a machine for making window envelopes, a roll couple for feeding window blanks in fanned out relation, said roll couple discharging the blanks with the leading ends unsupported, a second roll couple having its bite disposed at a lower level than that of said first-named couple, and a table between said roll couples, and along which the leading edges of the blanks are directed successively toward the bite of said last-named couple as said leading ends are inclined downward by gravity into contact with the table, the windowed portions of adjacent blanks being out of contact.

12. In an envelope blank patching machine, a run of mechanism comprising a pair of endless chain conveyors spaced apart, and respectively having means to align and feed an envelope blank, and an intermediate conveyor in the space between said chain conveyors and adapted to exert exclusively frictional action to carry said blank from chain to chain across said space, whereby said blank will be aligned by the first chain, may be gripped without rupture during transfer by said intermediate conveyor, and will be re-aligned by the second chain conveyor.

13. The method of individualizing fanned out window envelope blanks, which comprises supporting the blanks in the form of a fanned out band, progressively advancing the band to deliver the blanks at the leading end of the band into an unsupported condition so that the blanks are caused to bend individually under the influence of gravity to separate the window areas of contiguous blanks at the leading end of the band from one another, and pulling the bent blanks with an accelerated movement individually from the band, each as it becomes the leading blank of the band.

14. In a sheet feeding conveyor, in combination, spaced apart driving and driven pulleys, a driven conveyor belt passing over said pulleys, at least three small rollers disposed between said pulleys and also between the active and inactive stretches of the belt and in contact with the active stretch thereof, the axes of said rollers being disposed on an arc of large radius whereby the active stretch of the belt is supported with its sheet engaging surface in a convex curve of large radius, an opposed sheet gripping belt, and a pair of end rollers supporting said last named belt out of contact with said small rollers and with one of its surfaces in juxtaposed relation to the convexly curved sheet engaging surface of said driven belt.

FERDINAND L. SMITH.
ABRAHAM NOVICK.
